(57) **CLAIM**

The ornamental design for a dental implement, as shown and described.

DESCRIPTION

FIG. 1 is a front elevational view of a dental implement

showing my new design;

FIG. 2 is a rear elevational view thereof with an articulated joint illustrated at an angular orientation;

FIG. 3 is a top plan view thereof;

FIG. 4 is an end view thereof;

FIG. 5 is a front elevational view of an alternate embodiment illustrating a different dental tip;

FIG. 6 is a top plan view of the alternate embodiment;

FIG. 7 is an end view of the alternate embodiment;

FIG. 8 is a front elevational view of a further alternate embodiment wherein the tip comprises an interproximal brush;

FIG. 9 is a top plan view of the further alternate embodiment;

FIG. 10 is an end view of the further alternate embodiment;

FIG. 11 is a front elevational view of a further alternate embodiment wherein the tip comprises a sulka brush;

FIG. 12 is a top plan view of the FIG. 11 embodiment; and,

FIG. 13 is an end view of the FIG. 11 embodiment.

The rear elevational view of the embodiment are identical to the front elevational views illustrated in FIG. 5, FIG. 8 and FIG. 11 respectively, the bottom views are identical to the top plan views illustrated in FIG. 6, FIG. 9 and FIG. 12 respectively. The ends not illustrated are plain and unornamented and the handles shown in dashed lines do not form part of the design.
